LOUIS BRESIN, OF NEW YORK, N. Y., ASSIGNOR TO ADAMS-WILLIAMS MANUFACTURING CORPORATION, OF NEW YORK, N. Y., A CORPORATION OF NEW YORK.

CONVERTIBLE AUTOMOBILE BODY CONSTRUCTION.

1,413,704.

Specification of Letters Patent. Patented Apr. 25, 1922.

Application filed September 5, 1919. Serial No. 321,790.

To all whom it may concern:

Be it known that I, LOUIS BRESIN, a citizen of Russia, and resident of New York, borough of Manhattan, in the county of New York and State of New York, have invented certain new and useful Improvements in Convertible Automobile Body Constructions, of which the following is a specification.

This invention is an improvement in that 10 type of automobile body construction in which removable panels are provided for detachable engagement with the upper edge of the stationary and movable wall sections of the body of an automobile for converting the 15 body into one of a closed or an open type at will.

In certain constructions now in use, as for instance, as shown in the Williams application, Serial No. 71,516, filed January 11, 1916, 20 the panels have rigid frames, transparent panes, and depending lugs adapted to enter and be clamped in sockets provided in the body wall sections.

One object of my invention is to avoid the 25 use of these sockets in the body wall sections, which under some circumstances may become filled with dust and dirt. A further object is to provide a clamping mechanism including a cam easily operable through a 30 comparatively short range to clamping or releasing position instead of a screw which is harder to tighten or loosen. A further object is to avoid the use of lugs or other projecting parts on the panel and to provide 35 clamping members which will engage in recesses or apertures in the frame of the panel. A further object is to so construct the panel frame and clamps that the frame may seat directly on the wall and the clamps will be 40 entirely concealed from the exterior when in use. A further object is to provide a clamp which will present no projecting parts or recesses when the panel is removed and the clamp is not in use. A further object is to 45 provide means whereby the panel may be clamped in any desired tilted position and the angle of tilt readily adjusted at any time. A further object is to provide a cam operating means for the clamp which will lock the 50 clamp member in either of two limiting positions and prevent looseness or rattling when the panel is in position or when removed. A further object is to provide suitable operative adjustment between the clamp member and

the cam so that less accuracy is needed in 55 construction and installation and wear, variations in metal thickness, carelessness in workmanship, etc., may be easily compensated for.

I have illustrated one form of my invention in the accompanying drawings, in which:—

Figure 1 is a perspective view of a portion 60 of a vehicle body showing the panels in position and the door open.

Figure 2 is a vertical section taken for instance on the line 2—2 of Figure 1.

Figure 3 is a horizontal section on the line 65 3—3 of Figure 2, and

Figure 4 is a section similar to Figure 3 70 but showing the panel removed.

I have shown my invention as applied to a vehicle body having one or more stationary wall sections 10, and one or more movable wall sections 11, hinged to serve as doors. 75 The wall sections carry panels 12 and 13, each having a glass pane 14, and a rigid metal frame 15. The upper edges of the panels are designed to engage with the top of the vehicle. I have illustrated only a portion of 80 such top in the form of an angle iron or channel 16 which may constitute a side bow of a collapsible top, such for instance as is shown in my Patent 1,294,038 issued February 11, 1919, or which may be a part of a permanent 85 or removable rigid top. As the upper edges of the panels carried by the stationary wall sections of the vehicle may engage in or be suitably secured to the top of the vehicle, it is not as essential to have the rigid type of 90 clamping means at the lower edge as it is at the lower edges of the panels carried by the movable wall sections serving as doors. Obviously in opening the door the upper edge 95 of the panel must leave the frame of the top and when the door is open the panel must be supported solely at its lower edge and entirely by the door. In other words, my invention may be employed in connection with the panels for the stationary wall sections 100 as well as for the doors but is particularly adapted for the latter.

The clamping means may be incorporated in the frame of the wall section at the time the body is built or the sheet metal covering 105 of the wall section may be temporarily removed and replaced after the mechanism has been secured within sockets cut in the frame,

The clamps may be installed in separate molding strips adapted to be secured to the upper edges of the wall sections of vehicle bodies previously completed or already in use.

The frame of the panel in connection with which I have illustrated my invention includes inner and outer sheet metal walls 16 and 17 spaced apart to a distance slightly 10 greater than the thickness of the glass of the panel. Between these two walls I insert a block or metal plate of such thickness as to snugly fit between the two sheet metal walls and secure it in place in any suitable manner, 15 as for instance, by soldering, pressing, electric welding, or by rivets or screws. There are preferably provided two of these blocks or plates and one adjacent to each corner in the lower member of the frame and each 20 has a recess 19 therein extending up from the open lower end and presenting bevelled or inclined walls converging toward the sheet metal wall 16. The latter has an opening in the side thereof corresponding to and 25 registering with the narrow side of this recess.

The body wall of the vehicle has the usual wooden frame 20 which may be covered by an outer layer of comparatively thin sheet metal 21. The wall is 30 shown as so formed as to present a substantially horizontal seat or ledge portion 22, and an upstanding flange or ridge portion 23 between the seat and the inner surface 35 of the wall sections. This flange or ridge portion presents a substantially vertical side 24 which is substantially at right angles to the seat or ledge 22. When the invention is to be incorporated in a vehicle 40 body at the time the latter is built, the portion projecting above the seat 22 is formed as an integral part of the frame of the door, but if the invention is to be applied to a vehicle wall section already completed, the 45 upstanding flange or ridge portion 23 may be a separate strip secured to the upper edge of the wall section and of less width than the latter so as to leave exposed a portion of the upper surface of the wall section 50 to present the seat or ledge 22.

At points along the length of the flange portion 23 corresponding to the positions of the recesses 23 in the panel, I provide clamping members 25 adapted to enter the recesses 19. Each clamping member is of a form corresponding to that of the recesses, that is, it has a head portion of a thickness slightly less than the thickness of the block or plate 18 and of such a width and with 60 such bevelled edges, that it may slide up into the recesses but cannot be pulled horizontally out through the side of the latter. In other words, the maximum width of the head of the clamp 25 is wider than the minimum width of the recesses. The clamping 65

member is so positioned that it may project out from the wall 24 and the panel may be lowered into position with the recesses slipping over the clamps until the panel seats on the ledge 22 and rests against the vertical wall 24. Means are provided for pulling the clamps horizontally to force the panel against the vertical wall 24 and prevent it from being moved up off the clamp heads. This means, as illustrated, includes a link 70 75 26 projecting horizontally to the inner surface of the wall section and there provided with a cam member 27, which may engage with the inner surface of the wall and act to pull the link lengthwise. The cam member is of such form that it may hold the clamping member in any one of three positions. It has a face 28 nearest to the pivot connecting the cam member and the link and so formed that when this face engages with the inner surface of the wall, the clamp will project beyond the wall 24 and will permit the loose sliding of the panel into position. The cam also presents a surface 29 which is 80 85 a slightly greater distance from the pivot than is the surface 28 so that when the cam member is moved to the position indicated in Figure 3, the clamp will be drawn in to hold the panel rigidly in position. The cam member also presents a third face 30 opposite to the face 29 so that when the cam member is swung in the opposite direction to bring the surface 30 into operation, the link will be pulled through to the maximum position. When in this position it enters a recess 31 formed in the side of the wall 24 and 90 the outer surface of the clamp lies substantially flush with the outer surface of the wall 24 as indicated in Figure 4.

To prevent wear and to give the necessary 105 backing to the cam when in its clamping positions, I preferably embed a reinforcing strip of metal 32 in the wood frame in the rear of the outer thin sheet metal covering 21 and also provide a washer or other disk 110 member for direct engagement with the cam faces and encircling the link 26.

To permit of the desired adjustment and also the inclination or tilting of the panel, the link 26 is preferably made of three sections 34, 35, and 36. Two of these sections, for instance, 34 and 35 are pivotally connected so that the head of the clamp may swing to a limited extent in a vertical position and accommodate itself to the slot or recess of the panel even though the latter be tilted to lie at a few degrees off the right angle to the general direction of the link. Two of the links, for instance, 35 and 36 are threaded together so that the total effective 120 length of the link may be varied at will. In assembling, the link section 36 may be rotated in respect to the planes of the link and the clamp so as to increase or decrease the total effective length and cause the clamp 125 130

to come to proper operative position when the cam is moved to its limiting positions. The difference in distance from the pivot of the cam to the face 29 and to the face 30 5 should be such that when the cam is in the position shown in Figure 3 it will tightly clamp the panel and when in the position shown in Figure 4 it will equally tightly hold the clamp in the recess 21 and prevent 10 any rattling of the parts. Although the wall or face 24 is shown as being substantially at right angles to the seat 22 and substantially parallel to the general plane of the door, it will of course be evident that this wall or 15 face 24 may be inclined inwardly or outwardly to give the panel the desired tilt. It will also be evident that spacers may be inserted between the panel and either the upper edge or the lower edge of the wall 24 to vary 20 the tilt in either direction after the device is installed. A simple and effective means for varying this tilting is a pair of screws 37 extending into the wall 24 close to the lower edge of the latter. The heads of these screws 25 may be slightly rounded so as to project outwardly a slight extent from the plane of the wall 24 on each side of the clamp. By means of a screw driver these screws may be adjusted to vary the extent to which their heads 30 project. In placing the panel in position it will engage with the heads and with the upper edge of the wall 24, so that said heads and said edge constitute stops or abutments on opposite sides of the clamp. Due to the 35 comparatively short distance between the screw heads and the upper edge, the comparatively slight adjustment of the screw heads will give a very much greater adjustment of the upper edge of the panel and 40 cause it to bind to any desired degree against the frame of the top when the door is closed and thus prevent rattling. It will of course be evident that the screws might be near the upper edge of the wall 24 so that the panel 45 would seat against their heads and against the lower edge of the wall in case it is desired to vary the tilt outwardly. The pivotal connection in the link between the cam and the clamp head permits the head to automatically adjust itself to the inclination of 50 the panel. Both the adjustable length and the pivotal features of the link may be omitted where the devices are being manufactured in quantity of uniform size for the 55 same type of car but these features are particularly important where the device is made up in quantity for use with a wide variety of cars.

It will be noted that the clamp receiving 60 slot of the frame extends upwardly from the lower edge of the spacing plate 18 and the inner side wall 16 but that there is no corresponding slot in the upper wall 17. Thus the clamping head is entirely concealed when 65 the panel is in position. It will of course be

evident that there might be a corresponding slot in the wall 17 and that the head might come all the way through the frame and engage with the outer surfaces of the latter.

With my improved construction, the panel 70 is effectively held in position even though the cams should accidentally work loose or fail to hold properly. With the panel in position, it cannot move downwardly by reason of its engagement with the ledge or seat 22 and 75 cannot move outwardly to any material extent as the cam even when in released position permits only a limited outward movement of the clamping head. Thus when the panel is in position it cannot fall off even 80 though the clamps are not secured and can be removed only by lifting it vertically until the clamping heads come out of the slots.

Having thus described my invention what I claim as new and desire to secure by Letters Patent is:—

1. A vehicle body wall presenting a substantially horizontal ledge and a substantially vertical surface adjacent to the upper edge of the wall, a removable panel seated on and supported by said ledge and adapted to extend from said wall to the top of the vehicle, the lower edge of said panel being laterally movable toward and from said surface, and means carried by said ledge for 90 forcing said panel laterally against said surface and holding it in position, said panel when in place entirely concealing from view the outer portion of said means.

2. A vehicle body wall presenting a ledge 100 and a substantially vertical surface adjacent thereto and extending upwardly therefrom, a removable panel seating on said ledge and having a vertical slot in its lower edge, and a member entering said slot upon the lower- 105 ing of the panel toward said ledge and longitudinally adjustable for clamping said panel against said surface.

3. A vehicle body wall, presenting a ledge and a substantially vertical surface extending upwardly therefrom, a removable panel seating on said ledge, means for varying the angle of the panel in respect to said vertical surface, and a clamping member engaging with said panel and extending substantially horizontally through said vertical surface to the opposite surface of the wall.

4. A vehicle body having a substantially vertical surface, a removable panel engaging with said surface and having a slot extending into its lower edge and a clamping member having a head portion engaging with said slot, and a body portion extending through said slot and said wall substantially horizontally.

5. In combination a vehicle body wall, a clamp member adapted to project from one vertical surface of said wall, a panel having a slot extending upwardly into its lower edge, into which said clamp member may 130

enter upon the lowering of the panel into position, said clamp member having a head portion wider than a portion of said slot, and means on the opposite surface of said wall for drawing said clamp member toward said first mentioned surface to clamp said panel against the latter.

6. In combination, a vehicle body wall, a clamp member adapted to project from the outer vertical surface of said wall, a panel adapted to be supported by said wall and extend vertically therefrom and having a recess adjacent to its lower edge and into which said clamp member may enter, and a cam on the opposite surface of said wall for drawing said clamp member toward said first mentioned surface to clamp said panel.

7. A vehicle body wall, a removable panel adapted to extend vertically therefrom to the vehicle top, a member having a clamping head adapted to engage with said panel adjacent to the lower edge of the latter, and a portion projecting through said wall, and means on the inner end thereof for drawing said head into clamping engagement with said panel.

8. A vehicle body wall, a removable panel, a member having a clamping head adapted to engage with said panel adjacent to the lower edge of the latter, and a portion of adjustable length projecting through said wall, and means on the inner end thereof for drawing said head into clamping engagement with said panel.

9. A vehicle body wall, a removable panel, a member having a clamping head adapted to engage with said panel adjacent to the lower edge of the latter and a portion of adjustable length projecting through said wall, and a cam on the inner end thereof for drawing said head into clamping engagement with said panel.

10. In combination, a vehicle body wall, a removable panel having its lower edge portion engaging with the upper edge portion of said wall, and clamping mechanism carried by said wall and including a head engaging with said panel, a link extending horizontally through said wall, and means at the inner ends of said link for drawing the latter endwise, and holding said head in clamping engagement with said panel.

11. In combination, a vehicle body wall, a removable panel having its lower edge portion engaging with the upper edge portion of said wall, and clamping mechanism including a head engaging with said panel, a link including two pivotally connected sections extending through said wall, and means at the inner ends of said link for drawing the latter endwise and holding said slot in clamping engagement with said panel.

12. In combination, a vehicle body wall, a removable panel having its lower edge portion engaging with the upper edge portion of said wall, and clamping mechanism including a head engaging with said panel, a link including two pivotally connected sections extending through said wall, and a cam at the inner ends of said link for drawing the latter endwise and holding said slot in clamping engagement with said panel.

13. In combination, a vehicle body wall, a removable panel having its lower edge portion adapted to engage with the upper edge portion of said wall, and a clamping device including a head adapted for clamping engagement with said panel, a link projecting through said wall and including two sections relatively adjustable longitudinally, and a cam at the inner end of the link for holding the latter in operative position.

14. A vehicle body wall having a recess in its lateral face adjacent to the upper edge, a removable panel adapted to extend from said wall to the vehicle top and having a slot in its lower edge, a clamp member carried by said wall and means for locking said panel to said wall with said member in said panel slot, or for retaining said member in said wall recess when the panel is removed.

15. A vehicle body wall having a recess, a removable panel having a recess, a clamping member, and a cam for locking said panel to said wall with said member in said panel recess or for retaining said member in said wall recess when the panel is removed.

16. In combination, a vehicle body wall, a panel, a clamping member for securing said panel to said wall, and a cam connected to said clamping member and having an operating portion for locking said member in one position with said panel secured in place, and a second operating portion for locking said member in a second position with said panel removed.

17. In combination, a vehicle body wall, a panel, a clamping member for securing said panel to said wall, and a cam connected to said clamping member and having an operating portion for locking said member in one position with said panel secured in place, and a second operating portion for locking said member in the second position with said panel removed, and a third operating portion for holding said clamping member in a third position permitting the attachment or removal of the panel.

18. A vehicle body wall, presenting a substantially vertical surface, one edge of which serves as a panel abutment, an adjustable abutment carried by said wall and spaced from said edge, a removable panel adapted to engage with said abutments, and a clamp carried by said wall and operatively engaging with said panel intermediate of said

abutments, whereby the inclination of the panel in respect to the wall may be varied by relative adjustment of said abutment.

19. A vehicle body wall, having a pair of spaced abutments one of which is adjustable in respect to the other and a clamping member therebetween, and a removable panel held against said abutments by said clamp whereby the angle of the panel may be varied.

20. A vehicle body wall, having a pair of spaced abutments and a clamping member therebetween, and a removable panel for engagement with said abutments and clamp, one of said abutments being at a higher elevation than the other and one of them being adjustable substantially horizontally to vary the inclination of said panel.

21. A vehicle body wall, having a pair of vertically spaced laterally facing abutments, a panel adapted to engage with said abutments, one of said abutments being horizontally adjustable to vary the inclination of the panel, and a clamping device projecting through said wall and having a head for engagement with the said panel intermediate of said abutments.

22. A vehicle body wall, having a pair of vertically spaced laterally facing abutments, a panel adapted to engage with said abutments, one of said abutments being horizontally adjustable to vary the inclination of the panel, a clamping device projecting through said wall and having a head for engagement with the said panel intermediate of said abutments.

diate of said abutments, and a pivotal connection to said head permitting a variation of the inclination of the head in accordance with the tilt of the panel.

23. In combination a vehicle body wall, having a substantially horizontal seat and a vertical surface extending upwardly therefrom, a pair of abutments adjacent the lower edge of said surface and adjustable substantially horizontally, a panel adapted to engage with said surface and rest upon said seat, a clamping head for engagement with said panel intermediate of said abutments, means upon the inner surface of the wall for holding said clamping head in operative position, and means permitting the automatic adjustment of the angle of said head to accommodate it to variations in the inclination of the panel.

24. In combination, a vehicle body wall, a removable panel, having a frame including two spaced substantially parallel sheet metal walls, a spacing plate therebetween, said plate and at least one of said sheet metal walls having registering slots extending up from the lower edge thereof, a clamping member carried by said body adapted to enter said slots upon the lowering of the panel into position on said wall, and means for forcing said clamping member endwise to clamp said panel to said body wall.

Signed at New York city, in the county of New York and State of New York, this 3rd day of September, A. D. 1919.

LOUIS BRESIN.
